UNITED STATES PATENT OFFICE.

DOUGLAS E. BONNER, OF NEW YORK, N. Y.

FOLDING COVER.

1,188,402.

Specification of Letters Patent. Patented June 27, 1916.

Application filed August 26, 1912. Serial No. 716,985.

To all whom it may concern:

Be it known that I, DOUGLAS E. BONNER, a citizen of the United States, and a resident of New York city, county and State of New York, have invented certain new and useful Improvements in Folding Covers, of which the following is a specification.

My invention relates to tops, hoods or covers particularly adapted for use on vehicles of any description, on motor boats and as awnings or covers of any description and more specifically relates to that type of top, hood or cover which may be raised or lowered at will. It is well known to persons skilled in the art that one person has great difficulty in raising and lowering existing types of folding tops and that at best the manipulation of such tops is very slow, especially if the top is large and heavy and oftentimes requires the assistance of another person to effect the desired result. My improvement substantially overcomes these objections and provides a top which may be raised and lowered by one person with comparative ease and a maximum of speed.

Other objects of my invention will appear from the description hereinafter and the features of novelty will be pointed out in the appended claims.

Reference is to be had to the accompanying drawings in which—

Figure 1 is a side elevation showing my improved top in its raised or operative position; Figs. 2 and 3 are similar views illustrating different positions assumed by the top during the lowering operation, Fig. 4 is a similar view showing the top fully lowered or folded; and Figs. 5 and 6 are enlarged fragmentary elevations showing details of my invention.

In the drawings as an illustration of my invention the top is shown as applied to an automobile body and comprises a main or rear bow 18 which has its free ends pivotally secured to brackets 19 located on opposite sides of the vehicle body, preferably near the rear thereof and another bow 21 which has its free ends pivotally secured to opposite members of the main bow 18. This bow 21 extends rearwardly and upwardly from the main bow 18 in the usual manner when the top is unfolded or raised as shown in Fig. 1, and forms therewith what might be termed a rear section. The top further comprises a secondary or front bow 8, the

free ends of which are provided with projections or studs 23 which are preferably formed with parallel flattened surfaces for the purpose to be more clearly set forth hereinafter. The bows 18 and 8 are connected together by means of members 14 and 10 pivoted thereto respectively at 16 and 7 and having their opposed ends pivotally secured to each other by means of a rule or stop joint or similar connection 12 capable of being broken only in an upward direction, said members thus forming an articulated link and being preferably duplicated at each side of the vehicle.

Braces 13 at opposite sides of the vehicle in the illustrated form of my invention have one end pivotally connected at 17 with the main or rear bow 18 at a point below the pivot 16 and their opposite ends pivotally connected to extensions or lugs 11 secured to or forming part of the members 10 and preferably depending therefrom in the unfolded or raised position of the top. The distance between each of the pivots 17 and 16 plus the distance between the pivots 16 and the center of the joints 12 is substantially equal to the distance from the center of the joints 12 to pivots 11 plus the distance between pivots 11 and 17. With this arrangement the parts are compelled to fold as shown in Figs. 2 and 3. The members 10, one at each side of the vehicle, are extended beyond the pivots 7 and have their outer ends pivotally connected by means of a rule or stop joint 4 with the free ends of an outrigger or peak bow 2, the said rule joint 4 being arranged to break downwardly only. Braces 5 at opposite sides of the vehicle have one end pivotally connected at 6 with the auxiliary bow 8 preferably at a point above the point 7, and their other ends pivotally connected at 3 to the outrigger or peak bow 2. Similarly here the distance between the pivots 6 and 7 plus the distance between the pivots 7 and the centers of the joints 4 is approximately equal to the distance between the centers of the stop joints 4 and pivots 3 plus the distance between the pivots 3 and 6. This arrangement compels the outrigger or peak bow 2 to fold adjacent and parallel to or in other words to move toward the auxiliary bow 8 as shown in Fig. 3 during the lowering of the top. It is to be understood that the usual cover 20 of fabric or any suitable material is secured to the bows in any suitable manner, the lower edge of said cover being

2

indicated in dotted lines in Fig. 1. In the raised or unfolded condition of the top the projections or studs 23 are located in apertures formed in the brackets 9, said brackets 5 being further slotted through their peripheries as indicated at 25, the width of said slots being less than the diameter of the apertures in the brackets 9. In other words these slots are wide enough to permit the 10 projections 23 to pass out of the apertures in the brackets 9 when said slots register with the flattened portions of said projections 23, but prevent removal of said projections 23 when in any other relative position. 15 With the projections 23 in the brackets 9 the bow 8 will extend upwardly therefrom and will be rigidly maintained in this position by means of the members 14 and 10 and the braces 13, while the outrigger or peak bow 2 20 will be suspended in front of the bow 8 and will be rigidly supported by means of the braces 5. If desired the usual straps 1 may be provided and connected in the usual manner with the peak bow and the vehicle body 25 to prevent undue vibration of the top. The braces 5 substantially prevent the weight of the bow 2 and top material and the pull exerted by the straps 1 from accidentally breaking the joint 12 upwardly. The braces 30 5 transform the downward pull on the bow 2 into a tension on braces 5 and a thrust almost horizontal on the members 10.

When it is desired to lower or fold my improved top the straps 1, if used, are first 35 released after which the joint 12 is broken in an upward direction. The outrigger or peak bow 2 is now pressed upward and rearward to cause the bow 8 to swing in the brackets 9 to the inclined or canted position shown in 40 dotted lines 26 in Fig. 6. In this position the flattened portions of the projections 23 register with the slots 25 and said projections may be readily passed through said slots to release the bow 8 from the brackets 45 9. A continued pressure on the peak bow 2 or on the bow 8 will cause the parts to assume substantially the position shown in Fig. 2 and to finally reach the position shown in Fig. 3, it being understood that the bow 50 8 may be canted or inclined and the projections 23 inserted through slots 28 and into apertures in brackets 15 located on the main bow 18 just before the position shown in Fig. 3 is reached, said brackets 15 being similar to the brackets 9. In its transit from 55 the raised position shown in Fig. 1 to the positions shown in Figs. 2 and 3 the entire forward portion of the top is suspended and prevented from dropping through the co- 60 operation of the members 10 and 14 and the brace 13. No attention need therefore be paid to the auxiliary bow 8 and the same is automatically kept out of contact with and free and clear of the vehicle body during the 65 above operation. If the rear pressure is now

further continued the top will finally assume the completely lowered position in Fig. 4. In order to secure a compact folded position the members 14 and 10 may be provided with recesses properly located to receive and accommodate the pivots 11 and 6 respectively as is shown best in Figs. 3 and 4.

When it is desired to raise the top a pressure exerted upward and then forward on the bow 8 will first bring the top from the position shown in Fig. 4 to the position illustrated in Fig. 3. A continued forward pressure exerted on the bow 8 will swing said bow in the brackets 15 and bring it to the inclined position shown by dotted lines 27 80 in Fig. 5. In this position the flattened portions of the projections 23 are in registry with the slots 28 and the said projections may be readily and easily removed from the brackets 15. The bow 8 may now be moved 85 toward the front of the vehicle and finally again inclined as shown by dotted lines 26 in Fig. 6 to permit the projections 23 to be inserted through the slots 25 into the openings in the brackets 9. After this has been 90 done the bow 8 is swung in said brackets to an upright position until the members 14 and 10 have straightened out and the outrigger or peak bow 2 properly positioned and further movement is arrested by the 95 stop joints 4 and 12 in which conditions of the parts the cover 20 is fully extended and completely covers the vehicle. The straps 1 if used may now be connected in the usual manner to secure the top against undue 100 vibration. As in the lowering or folding operation the forward portion of the top will be suspended out of contact with the vehicle body during its transit from the closed to the open or raised position. This 105 result is still further assured by locating the pivot 11 at a distance from the joint 12 and below a line drawn through the pivot 7 and the center of the joint 12 when the top is raised, an arrangement which will cause the 110 bottom of the bow 8 to move rearwardly in an arc having its crown upward. This construction makes it absolutely certain that the lower ends of the bow 8 during its forward and rearward movement will remain safely 115 above the sides of the vehicle body. While my device as shown does not compel bow 8 to remain parallel to the bow 18 during said forward and rearward movement, it is to be understood that additional members could be readily applied to compel it to do so 120 should this be desired. It will be seen that the bow 8 cannot be detached from or attached to the forward brackets 9 or rear brackets 15 without first being canted or inclined to a predetermined position so that 125 accidental dislocation of this bow and its connected parts is absolutely prevented. Instead of constructing the brackets 9 and 15 with slots as shown the same may simply be 130

provided with apertures into and from which the projections 23 are inserted and removed by a movement in an axial direction; accidental removal in this case being

6 prevented by means of cotter pins or the like. These cotter pins may also be used if desired in the form of my invention as illustrated and are indicated as 24 in Fig. 6.

In practice I prefer to duplicate the members 5, 10, 13 and 14 on each side of the top 10 and preferably on the outside of the cover 20 although said members could as readily be positioned inside of said cover if deemed advisable.

15 It will be clear that instead of the straps 1 I may provide any other means for steady- ing the top suitable for this purpose.

An important feature of my invention re- 20 sides in the fact that it can be applied to existing tops already in use and when so applied adds strength and rigidity thereto.

It is to be understood that, while I have shown and described my improvement in connection with an automobile, this is only 25 one instance of the many uses to which said improvement may be put. For instance, my improved top may be used in connection with any type of vehicle, or with any type of boat desired, and may further be utilized 30 as an awning to cover stationary objects, and the claims are to be construed accordingly. In addition to the above it will be apparent that additional bows such as 8 and additional connections such as shown may be pro- 35 vided to secure a top capable of covering a larger area than the one shown if found desirable. It is to be further understood that I do not limit myself to the exact and par- ticular arrangement shown and that various

changes in the specific form shown and de- 40 scribed may be made within the scope of the claims without departing from the spirit of my invention.

I claim:—

1. A folding cover comprising a main bow 45 movably connected with the element to be covered, a secondary bow adapted to be de- tachably secured to said element, an articu- lated link pivotally connected with each of 50 said bows, a peak bow pivotally connected with said link, a brace pivotally connected with said main bow and said link and a sec- ond brace pivotally connected with said sec- 55 ondary bow and said peak bow, said braces when in operative position extending in op- posite directions from a line drawn length- wise through said link.

2. A folding cover comprising a main bow 60 movably connected with the element to be covered, a secondary bow adapted to be de- tachably secured to said element, an articu- lated link pivotally connected with each of 65 said bows, a peak bow pivotally connected with said link, a brace pivotally connected with said main bow at a point below said link and also pivotally connected with said link and a second brace pivotally connected with said secondary bow at a point above 70 said link and also pivotally connected with said peak bow.

In testimony whereof I have hereunto set my hand in the presence of two subscribing witnesses.

DOUGLAS E. BONNER.
